Primary Examiner — Paula Greene(74) *Attorney, Agent, or Firm* — Ladas & Parry LLP(57) **CLAIM**

We claim the ornamental design for a speaker, as shown and described.

DESCRIPTION

FIG. 1 is the front perspective view of a speaker showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is a front perspective view thereof shown in an example environment; and,

FIG. 9 is a front perspective view thereof shown in another example environment.

The broken lines in the figures show portions of a speaker which form no part of the claimed design.

1 Claim, 9 Drawing Sheets(56)
